UNITED STATES PATENT OFFICE.

HUGH S. KERR, OF PHILADELPHIA, PENNSYLVANIA, ASSIGNOR TO ISRAEL FOSTER, OF SAME PLACE.

DESIGN FOR A CARPET-PATTERN.

Specification forming part of Design No. 5,205, dated August 15, 1871.

To all whom it may concern:

Be it known that I, HUGH S. KERR, of Philadelphia, county of Philadelphia, State of Pennsylvania, have invented or produced a Design for a Carpet-Pattern, of which the following is a specification:

In the accompanying drawings the figure represents sufficient of a carpet-pattern to illustrate my design, the principal features of which are the members A, B, and C. Each member A is of an octagonal shape, has a plain border, *a*, broken at regular intervals by short transverse bars *b*, and a central ornament, *c*, of the character represented. Each member B has an ornamental zigzag border, *d*, and a central figure, *e*; and each member C is of a cruciform shape, is ornamented by square or diamond-shaped dots, and has a broken foliated border, *f*. The corners of the adjacent members C are joined by scroll-like ornaments *h*, and the body of the carpet between the

several members is occupied by dots and foliated and other ornaments, as clearly shown in the drawings.

Irrespective of the colors employed, I claim—

1. The design for the member A, as described and illustrated.
2. The design for the member B, as shown and described.
3. The design for the members C, as described and represented.
4. The design for the whole pattern, including the members A, B, and C, and minor ornamentation.

In testimony whereof I have signed my name to this specification in the presence of two subscribing witnesses.

HUGH S. KERR.
